UNITED STATES PATENT OFFICE.

PHILANDER SHAW, OF BOSTON, MASSACHUSETTS.

IMPROVEMENT IN BOOTS AND SHOES.

Specification forming part of Letters Patent No. **38,766**, dated June 2, 1863; antedated October 18, 1862.

To all whom it may concern:

Be it known that I, PHILANDER SHAW, of Boston, in the county of Suffolk and State of Massachusetts, have invented certain new and useful Improvements in the Manufacture of Boots and Shoes; and I do hereby declare that the following, taken in connection with the drawings that accompany and form part of this specification, is a description of my invention so full and exact as to enable those skilled in the art to practice it.

My invention consists, first, in a new article of manufacture—viz., a boot or shoe in which a flexible “upper” is united with a sole made wholly or in part of compressed wood; and, second, in a detail of the manufacture, by which the upper and the whole or a fractional part of the sole of compressed wood are united.

Figures 1 and 2 are respectively a side view and plan of a shoe embodying my invention. Fig. 3 shows a section taken vertically and longitudinally through the shoe, and Fig. 4 shows a cross-section taken through the shank part of the shoe.

In construction in accordance with my invention the inner sole, *a*, is first temporarily fixed upon the last, and the upper *b* drawn over the last and secured to the inner sole. A metallic plate, *c*, of the proper curvature and outline is then placed upon the upper, where it is drawn over the inner sole, and the plate is then fastened to the inner sole and upper by small nails which are driven through the parts and clinched in the inner sole. Holes are made through the metallic plate for the reception of the nails or screws employed to secure the outer sole of compressed wood, or any part thereof, to the body of the shoe.

Where the wooden sole extends only under the heel and shank to the ball of the foot, leaving the remainder of the sole to be formed

of some flexible material to prevent that degree of rigidity which is possessed by a shoe having its sole entirely of compressed wood, the construction illustrated in Fig. 3 is that which I prefer to any other. It will be seen in the said figure that the metallic plate extends beyond the wooden part of the sole toward the toe of the shoe. The first lift of the flexible part of the sole is beveled, and nailed across the shoe through the plate *c* into the inner sole; or, if the flexible part of the sole be made of a single thickness, then the end thereof is notched, as illustrated, and the inside bevel of the sole nailed, as before described.

The wooden portion of the sole is beveled, as shown, to correspond to the beveling of the flexible part of the sole, and the outer part of the latter is united to the rigid part of the sole by nails or by screws, as shown.

While wood for the sole may be compressed in any suitable way, I prefer to prepare the wooden portion of the sole under and in accordance with the process patented to me on the 15th day of May, A. D. 1860, as wood thus prepared will not change its form materially, and will answer the requirements of hardness and impermeability desirable in a sole, while wood in an uncompressed state is utterly unfit to be used in the soles of boots and shoes.

I claim—

1. As a new article of manufacture, a boot or a shoe which is made of a flexible upper united with a sole composed wholly or in part of compressed wood.
2. The combined arrangement, operating substantially as shown and described, of the metallic plate *c* with the whole or a portion of the sole, when made of compressed wood.

PHILANDER SHAW.
